US0D1051167S

(12) **United States Design Patent** (10) Patent No.: **US D1,051,167 S**
(45) Date of Patent: ** Nov. 12, 2024

(54) **DISPLAY SCREEN OR PORTION THEREOF
WITH ICON**

(71) Applicant: **SHIMADZU CORPORATION**, Kyoto (JP)

(72) Inventors: **Kosuke Uchiyama**, Kyoto (JP); **Tomohiro Hirama**, Kyoto (JP); **Noriko Kato**, Kyoto (JP)

(73) Assignee: **SHIMADZU CORPORATION**, Kyoto (JP)

(**) Term: **15 Years**

(21) Appl. No.: **29/890,364**

(22) Filed: **Apr. 24, 2023**

(30) **Foreign Application Priority Data**

Nov. 25, 2022 (JP) ..... 2022-025397 D

(51) **LOC (14) Cl.** **14-04**

CLAIM

The ornamental design for a display screen or portion thereof with icon as shown and described.

DESCRIPTION

The FIGURE is a front view of a display screen or portion thereof with icon showing our new design.

The broken line at the periphery of the FIGURE illustrates a display screen or portion thereof and forms no part of the claimed design.

1 Claim, 1 Drawing Sheet
